No. 688,944.

Patented Dec. 17, 1901.

J. N. GAUDREAU.

POULTRY NEST.

(Application filed June 21, 1901.)

(No Model.)

FIG. 1. This diagram shows a top-down view of a rectangular frame divided into four quadrants. The top-left quadrant contains a circular component with concentric lines, labeled 32. A horizontal line labeled 16 passes through the center of this circle. A vertical line labeled 30 extends from the bottom of the circle to the bottom of the frame. A vertical line labeled 31 is positioned to the right of 30. The top-right quadrant contains a similar circular component with concentric lines, labeled 32. A horizontal line labeled 16 passes through its center. A vertical line labeled 30 extends from its bottom to the bottom of the frame. A vertical line labeled 31 is positioned to the left of 30. The bottom-left quadrant contains a circular component with concentric lines, labeled 32. A horizontal line labeled 16 passes through its center. A vertical line labeled 30 extends from its bottom to the bottom of the frame. A vertical line labeled 31 is positioned to the right of 30. The bottom-right quadrant contains a circular component with concentric lines, labeled 32. A horizontal line labeled 16 passes through its center. A vertical line labeled 30 extends from its bottom to the bottom of the frame. A vertical line labeled 31 is positioned to the left of 30. The frame has a central vertical line labeled 11 and a central horizontal line labeled 13. There are two small rectangular components labeled 18 on the left and right sides of the frame. The bottom edge of the frame is labeled 15 on the left and 10 on the right.

FIG. 2. This diagram shows a cross-sectional view of the device. It features a central vertical wall labeled 13. On either side of this wall are vertical panels labeled 11 and 11a. The panels are secured to the wall by brackets labeled 18. The panels are labeled 6 on their outer edges. The central wall 13 has a central vertical slot labeled 28. The bottom of the central wall 13 is labeled 20. The base of the device is labeled 14 on both the left and right sides. The base is supported by a central vertical column labeled 3. The base is labeled 21 on both the left and right sides. The base is labeled 22 and 24 on the left side, and 23 and 24 on the right side. The base is labeled 25 on both the left and right sides. The base is labeled 7 on the right side. The base is labeled 10 on the right side. The base is labeled 15 on the right side. The base is labeled 16 on the right side. The base is labeled 30 on the right side. The base is labeled 31 on the right side. The base is labeled 32 on the right side. The base is labeled 14 on the left side. The base is labeled 5 on the left side. The base is labeled 21 on the left side. The base is labeled 18 on the left side. The base is labeled 3 on the left side. The base is labeled 20 on the left side. The base is labeled 14 on the left side. The base is labeled 14 on the right side. The base is labeled 5 on the right side. The base is labeled 21 on the right side. The base is labeled 18 on the right side. The base is labeled 3 on the right side. The base is labeled 20 on the right side. The base is labeled 14 on the right side.

FIG. 3. This diagram shows a side view of the device. It features a central vertical wall labeled 11a. The base of the device is labeled 21 on both the left and right sides. The base is labeled 22 and 24 on the left side, and 23 and 24 on the right side. The base is labeled 25 on both the left and right sides. The base is labeled 21 on both the left and right sides. The base is labeled 18 on the left side. The base is labeled 10 on the right side. The base is labeled 28 on the right side. The base is labeled 29 on the right side.

UNITED STATES PATENT OFFICE.

JOSEPH N. GAUDREAU, OF MAGOG, CANADA.

POULTRY-NEST.

SPECIFICATION forming part of Letters Patent No. 688,944, dated December 17, 1901.

Application filed June 21, 1901. Serial No. 65,402. (No model.)

To all whom it may concern:

Be it known that I, JOSEPH N. GAUDREAU, a subject of the King of Great Britain, residing at Magog, county of Stanstead, Province of Quebec, Canada, have invented certain new and useful Improvements in Poultry-Nests; and I do hereby declare that the following is a full, clear, and exact description of the invention, such as will enable others skilled in the art to which it appertains to make and use the same.

My invention relates to improvements in poultry-nests; and the primary object in view is the provision of an improved construction wherein freshly-laid eggs are automatically and safely re-stored in a separate compartment from the nest chamber or chambers, whereby egg-eating hens are prevented from eating the eggs.

A further object is the provision of an improved structure adapted to enable an attendant to reach and remove the eggs without disturbing the occupant of either of a series of nest-chambers, to simplify and cheapen the construction, and to prevent the nest-egg from being lost or removed, while permitting it to have a limited movement in the nest-chamber.

With these ends in view the invention consists in the novel construction and arrangement of parts, which will be hereinafter fully described and claimed.

In the drawings hereto annexed, forming a part of this specification, Figure 1 is a plan view of a poultry-nest embodying my invention. Fig. 2 is a longitudinal section thereof on the line 2 2 of Fig. 1. Fig. 3 is a vertical cross-section on the line 3 3 of Fig. 2.

The same numerals of reference denote like parts in all the figures of the drawings.

5 designates the frame or casing, which is shown as of generally rectangular construction, although the particular shape is not material. Within this casing are secured the 45 transverse partitions 6 and 7, which are arranged parallel with each other and serve to form an intermediate storage-compartment 8 and to define the limits of the nest-chambers 9 10. The upper portion of the storage-compartment 8 is closed by means of a door or cover, which is represented in the drawings as consisting of two sections 11 11^a, hav-

ing individual hinge connection 12 with the partitions 6 7, said parts of the cover arranged to meet one with the other when they 55 are closed to the position shown by Fig. 2, and the cover member 11 having a suitable operating-knob 13.

Each nest-chamber is formed with a bottom 14, in which is formed a cavity 15, and the 60 bottom 16 of this cavity is inclined from the end wall of the casing 5 in a downward direction toward an opening 17, the latter being formed or provided in each of the partitions 6 or 7. (See Fig. 2.)

The storage-compartment 8 lies between the two nest-chambers 9 10, and it contains a 65 sliding drawer 28, which extends across the structure and is arranged to be withdrawn and replaced from the outside of the device. 70

The drawer may be manipulated by an external knob 29, and the eggs in the drawer can thus be easily reached and removed without disturbing the hen or hens on the nest. This drawer is furnished with a false bottom 18, 75 which may be made of any suitable material and which is arranged, as shown by Fig. 3, so as to produce a space 19, adapted to contain a filling of cushion material 20. This soft or cushioned false bottom of the drawer is arranged below the inclined bottoms 16 of the nest-chambers, so that the freshly-laid eggs may roll along said bottoms from the nest-chambers into the drawer in the storage-compartment 8, the cushioned false bottom in 80 said drawer having a tendency to minimize breakage of the eggs. This storage-compartment is provided with the linings 21 on its side walls, and the eggs may thus be safely received and stored in the compartment 8, 90 the latter adapted to receive the eggs from a series of nest-chambers.

Within the compartment 8 and attached to the partitions 6 7 of the poultry-nest are the plates 22 23, one of which is shown by Fig. 3 95 as having a pivotal connection at 24 to one of the partitions. To each of these plates is connected a flap-door 25, the same having a pivotal connection 26 with the plate, said pivot 26 lying at right angles to the pivot 24. 100 The flap-door is arranged to cross one of the openings 17, so as to cut off communication between one of the nest-chambers and the storage-compartment, thus preventing an

egg-eating hen from having access to the eggs which may be contained in the intermediate compartment 8. This door is held normally in its closed position by its own weight or gravity; but the door is free to have a universal movement with respect to the partition, because the door itself is connected by a pivot lying in one direction to a plate, which has a movable connection with the partition by a pivot lying in a different direction, whereby the door is adapted to easily and freely open when pressure is exerted thereon by an egg rolling down the bottom 16 of the nest-chamber. A freshly-laid egg is thus adapted to automatically open the door in order to permit the egg to pass from a nest-chamber into the storage-compartment, and communication between the two chambers is automatically cut off by the closing of the door. If desired, the cover 11 11^a may be opened to remove the eggs from the compartment 8 through the top thereof.

Each chamber 9 or 10 has a nest-egg 30. As shown by the drawings, the egg is attached to a cord 31, which is fastened to the bottom of the nest at 32, whereby the egg is prevented from being easily removed, and at the same time it is adapted to have a limited movement in the nest-chamber.

Changes within the scope of the appended claims may be made in the form and proportion of some of the parts, while their essential features are retained and the spirit of the invention is embodied. Hence I do not desire to be limited to the precise form of all the parts as shown, reserving the right to make changes therein within the scope of the invention.

Having thus described my invention, what I claim as new is—

1. A poultry-nest comprising a casing having transverse partitions and forming an intermediate storage-compartment between separate nest-chambers, the latter having inclined bottoms terminating at door-openings formed in said partitions, and automatically-closable

doors arranged to cut off communication between said storage-compartment and the nest-chambers, said doors being opened automatically by eggs rolling against them, substantially as described. 50

2. A poultry-nest comprising a casing having the transverse partitions arranged to form an intermediate storage-compartment and to divide the casing into isolated nest-chambers, 55 suitable door-openings in said partitions, a cover to the storage-compartment, the inclined bottoms in the nest-chambers, and the hinged doors arranged within the storage-compartment and mounted on the partitions 60 to normally close the door-openings therein, said doors adapted to be opened by eggs rolling against them and being closable automatically and cutting off communication between the storage-compartment and the nest-chambers, substantially as described. 65

3. A poultry-nest comprising a casing having the transverse partitions forming an intermediate storage-compartment between isolated nest-chambers, the inclined bottoms in 70 said nest-chambers, the door-openings in the partitions, a drawer having a cushioned false bottom and disposed within the storage-compartment and below the inclined bottoms of the nest-chambers, the lining within the storage-compartment, the hinge-plates pivoted to the partitions above the door-openings, and the doors hinged to the door-plates, substantially as described. 75

4. A nest provided with nest-chambers and 80 with an intermediate storage-chamber, a drawer within said storage-chamber, and means for normally cutting off communication between the chambers, substantially as described. 85

In witness whereof I have hereunto set my hand in the presence of two witnesses.

JOSEPH N. GAUDREAU.
